[57] **CLAIM**

The ornamental design for a tire tread, as shown and
described.

DESCRIPTION

FIG. 1 is a perspective view of a tire tread showing our new
design, it being understood that the tread pattern is repeated
throughout the circumference of the tire tread, the opposite
side being the same as that illustrated; and.

FIG. 2 is an enlarged fragmentary front elevation view of the
tread pattern of FIG. 1 showing our new design.

The broken line disclosure of a tire bead and sidewall is for
illustrative purposes only and forms no part of the claimed
design.
